DEEP FAT FRYER

Max Steinbook, New York, N. Y., assignor to The Peerless Corporation, New York, N. Y., a corporation of New York

Application September 21, 1953, Serial No. 26,886

Term of patent 14 years

(Cl. D81—10)

To all whom it may concern:

Be it known that I, Max Steinbook, a citizen of the United States and a resident of the city, county, and State of New York, have invented a new, original, and ornamental Design for a Deep Fat Fryer, of which the following is a specification, reference being had to the accompanying drawing, forming part thereof. The figure is a perspective view of a deep fat fryer embodying my new design. The end not shown is like the end disclosed and the other side is plain.

The essential features of my design reside in the portions shown in full lines.

I claim:

The ornamental design for a deep fat fryer, as shown and described.
